ATTORNEY

UNITED STATES PATENT OFFICE

ABRAHAM D. BORENSTEIN, OF BROOKLYN, NEW YORK

HOSE SUPPORTER AND THE SUSPENDING MEANS THEREFOR

Application filed March 30, 1928. Serial No. 265,953.

This invention relates to a hose supporter and the suspending means therefor.

The object of the invention is the production of a hose supporter and the suspending means, on a garment therefor. The second object of the invention is the production of a hose supporter provided with a pair of appurtenances to connect it to a garment. The third object of the invention is the production of a hose supporter which can be easily and quickly detached from a garment to which it has been connected. The fourth object of the invention is the production of means connected to a garment for supporting the hose supporter and which means will not injure or tear said garment.

In the accompanying drawings Fig. 1 represents a front elevation of the improved hose supporter suspended from a garment; Fig. 2 shows an enlarged section of Fig. 1 on the broken line 2, 2; Fig. 3 indicates a section of Fig. 1 on the broken line 3, 3; Fig. 4 shows an enlarged fragmentary portion of Fig. 2; Fig. 5 shows a section similar to Fig. 4 with a modification and Fig. 6 shows a section similar to Fig. 4 with a further modification.

The main strap 20 of the hose supporter comprises a piece of webbing preferably elastic and at the upper end of which is indicated an ordinary safety pin with its bar 21, its pin proper 22 and its keeper 23. A clevis is indicated with its lower member 27 and the hook ends 28. The said hook ends are suspended from the bar 21.

A supporting strap is shown having the members 30 and 31. Each of said members has formed therewith the upper fold 32 from which descends the leg 33. At the lower end of the latter is formed the fold 34. The leg 35 rises from each of the folds 34 and the crown 36 connects the legs 35. A U shaped clamping bracket 40 engages the legs 33 and 35 and eyelets 41 clamp the bracket 40 and the legs 33 and 35 together.

A garment is indicated at 45 with the depending strap 46. In the strap 46 are supported two eyelets 47 through which the pin 22 passes. In the strap 46 is formed an opening 48, in which is tightly seated the eyelet 49. A thimble 50 having the flange 51 is

tightly seated in the eyelet 49 and has an end upset to form the flange 52. The flange 51 bears against one of the flanges of the eyelet 49. A second thimble 53 is supported on the thimble 50 and bears against the eyelet 49 and the flange 52. The crown 36 of the legs 35 of the supporting strap is supported on the thimble 53.

A bar 55 extends between and is supported on the hook ends 28. The upper end of the strap 20 is supported on the bar 55 and is wound around the same as indicated with its legs 56 and 57. A pair of eyelets 58 clamp the bar 55 and the leg 57. The strap 20 at its lower portion is clamped by the buckle indicated in its entirety by the numeral 60. The said buckle comprises the upper cross bar 61, the intermediate cross member 62 and the hook ends 63. A wing 64 having the serrated member 65 is hinged to the cross bar 61 in the usual manner. At the lower end of the strap 20 is clamped the U shaped bracket 66, by means of the eyelets 67.

A lower strap is indicated having the members 68 and 69. The said members engage the hook ends 63 and are folded over the intermediate cross bar 62. An eyelet 70 connects the members 68 and 69 and their upper folded portions together. Intermediate portions of the members 68 and 69 have each formed therewith a loop 75 each with a rising portion 68^a, which are each maintained in proper position by means of the washer plates 76 and 77 and said plates are clamped in place by the eyelets 78. Each rising portion 68^a is folded over at 68^b and from the latter descends the portion 68^c. At the lower end of the latter is formed the fold 68^d. From the latter rises the portion 68^e, which is engaged by one of the eyelets 78, and has formed therewith the portion 68^f. A washer plate 82 bears against the inner face of each of the portions 68^e. A pair of eyelets 83 engage and clamp together the member 68^e and the washer plate 82. A thimble 84 extends through each of the eyelets 83. On the outer ends of the thimbles 84 are located the sleeves 85 each having the flange 86. An elongated tapered stud 90 is supported on each pair of the thimbles 84, and bears between the flanges 86 and between 100

one of the flanges of each of the eyelets 83. A clasp for each of the members 68 and 69 is indicated with its upper cross member 91, the curved side members 92 the lower parallel members 93, which latter are connected by the curved lower crown 94.

Referring to the modification shown in Fig. 5 the depending strap is again indicated at 46, with its opening 48. The thimble 50 is again indicated having the flanges 51 and 52 and is in this instance directly supported in the opening 48. A washer 95 is supported on the thimble 50 and bears against the strap 46. A second thimble 96 is supported on the thimble 50 and bears between its flanges 52 and the washer 95. The crown 36 of the legs 35 of the supporting strap is supported on the thimble 96.

Referring to the modification shown in Fig. 20 6 the depending strap is again shown at 46 with its opening 48. The thimble 50 is again indicated with the flanges 51 and 52, and is directly supported in the opening 48. A washer 97 is supported on the thimble 50 and bears against the strap 46. A second washer 98 is supported on the thimble 50 and bears against the flange 51. A thimble 99 is supported on the thimble 50 and bears between the strap 46 and the washer 98. The crown 20 36 of the legs 35 of the supporting strap is supported on the thimble 99.

Various modifications may be made in the invention and the present exemplification is to be taken as illustrative and not limitative thereof.

Having described my invention what I desire to secure by Letters Patent and claim is:

1. In combination, the main strap of a hose supporter, a clevis supporting the upper end 40 of the strap, a safety pin having a bar and pin proper, said safety pin supporting said clevis, a depending strap of a garment adjacent to said safety pin, a supporting strap having a pair of members, each of said members having a pair of legs folded on each other, a clamping bracket encasing said legs, a pair of eyelets clamping said bracket and the legs together, said bracket also engaging the bar of the safety pin, the members of 50 the supporting strap joining at their top portions with a crown and means to suspend said crown from a garment.

2. In combination, the main strap of a hose supporter, a supporting strap suspending 55 said main strap, a support having an opening, an eyelet in said opening fastened to said support, a thimble extending through said eyelet and means to maintain said thimble in operative position in said eyelet, said thimble supporting said supporting strap.

3. In combination, the main strap of a hose supporter, a supporting strap having a pair of members connected to said main strap, a garment, an eyelet extending through an opening in said garment, a thimble having a

flange at each end extending through said eyelet, and a second thimble supported on the first thimble with its ends bearing against said eyelet and one of the flanges of the first thimble, said supporting strap supported on 70 said second thimble.

Signed at the borough of Manhattan, city of New York in the county of New York and State of New York this 19th day of March, A. D. 1928.

ABRAHAM D. BORENSTEIN.
